STRETCHING AND SPUDDING MACHINE

William Green, Gloversville, N. Y.

Application January 13, 1943, Serial No. 472,235

15 Claims. (Cl. 69—34)

This invention relates to machines for working leather by stretching and spudding preparatory to utilizing it in the manufacture of gloves or for any other purpose.

It is of the greatest importance in the manufacture of leather gloves that each skin should be preliminarily stretched longitudinally throughout its entire area from edge to edge in a complete and adequate manner. By this I mean that all areas of the skins should be stretched substantially to their elastic limit regardless of irregularities in shape or differences in size and texture of the treated skin. The stretching operation has been heretofore carried out by hand, and, besides requiring considerable skill and experience on the part of the operator, is very fatiguing and tedious, so that toward the end of the day the quality of the work almost invariably suffers. It is difficult also to find operators having the physical strength, endurance and disposition to engage in this branch of the glove making industry.

Spudding is an operation related to stretching and consists in distorting or bending the matted fibres of the skin while under tension to force that re-arrangement of the fibres best adapted to allow full flow of the leather in any selected direction. Heretofore spudding has also been a hand operation usually performed by grasping a small area of the skin in one hand and dragging its edge past and about a dull blade. In spudding, while the force applied is not great it is restricted in its application to such a small area of the skin that the tension per unit area is sufficient to work the leather out to its full extension in the desired direction, and consequently to bring about a resulting contraction along the dimension at right angles to the spudding action. Operators have almost invariably heretofore slighted spudding of the edge portions of the skin.

With these considerations in view it is an object of the present invention to provide a new and improved machine for stretching and spudding skins of leather by employing which the operator will be relieved of the necessity to exert any substantial physical strength but may control the stretching and spudding functions of the machine in the most delicate, accurate and quickly-responsive manner and so improve both the economy of the process and the quality of the product.

To this end an important feature of my invention consists in a machine having a transverse skin-holding or retarding member in combination with a flight of power-driven slats movable con-

tinuously away from the holding member and associated with a manually operated presser or hold-down acting to create a readily-controlled frictional traction between the skin and the moving slats. These slats may be appropriately referred to as "traction slats."

The skin-holding or retarding member may take the form of a horizontal bar or board over which one end of the skin may be draped at a height convenient for the operator to engage and hold the skin between the bar and his own body, while both hands are free to manipulate the hold-down and the skin which will now rest, as on a table, upon the traction slats moving in a path substantially level with the bar and away from it and from the operator.

The traction slats are arranged parallel to the skin-holding bar and are guided and supported for movement in a predetermined path which may be substantially horizontal or upwardly and rearwardly inclined as herein shown. Many features of my invention consist in constructional details of the means for supporting, guiding and driving the traction slats with a view to securing free, continuous and uniform movement thereof without distortion or binding, and without danger of tearing the skin being treated or injuring the operator handling it. These features will be discussed in detail hereinafter.

Another important feature of the invention consists in a flight of traction slats each having an abrupt edge or vertex over which the skin may be flexed in developing tension therein and in carrying out the spudding treatment of the leather. As herein shown the most effective contour of slat is secured by undercutting the advancing face of each slat, or rib thereon, so that the face makes a retreating angle to the path of the slats. Such angle is advantageous in that it tends to retain the hold-down blade in position instead of displacing it in the operation of the machine.

An essential element of the machine of my invention is a presser or hold-down member for creating friction traction between the skin and the traction slats moving beneath it. It is within the scope of my invention to employ a flat presser member effective merely to press the skin upon the top surface of the traction slats, but in general best results are secured by employing a hold-down member having a long thin blade with a blunt edge about which the skin may be abruptly flexed and by which it may be pressed into contact with the inclined face of any slat in the moving flight.

The machine of my invention is also valuable in the tanning industry as a staking machine. The tanner is supposed to turn his leather over to the glove manufacturer thoroughly staked; that is, made pliable by manipulation over a dull blade edge. In that operation the tanned leather is abruptly contorted while under substantial tension and stiffness imparted to it in tanning is thereby worked out of the leather. The so-called "leather" characteristic of glove leather is largely attained and accentuated by the staking treatment. Staking of glove leather, as distinguished from heavier shoe leather, has largely been carried out hitherto by so-called arm staking or knee staking, both of which are arduous and fatiguing operations. Further in the staking operation edge treatment of the skins becomes a difficult, slow and ineffective operation. The employment of my machine in the manner described relieves the operator of exhausting demands upon his strength. Further, instantaneous control of the force applied to the skin is available to the operator and in his earliest experience with the machine become reflex. The machine of my invention accordingly, operated with the assistance of properly designed hand tools achieves a complete and efficient staking treatment of glove leather.

These and other features of the invention will be best understood and appreciated from the following description of a preferred embodiment thereof selected for purposes of illustration and shown in the accompanying drawings, in which—

Fig. 1 is a view in perspective of the complete machine as seen from the front, a skin of leather being shown thereon in dotted lines.

Fig. 2 is a view in side elevation, showing a portion of the frame broken away.

Fig. 3 is a fragmentary view in rear elevation, the machine being represented as having two slats removed to expose the shaft and sprockets which would otherwise be concealed.

Fig. 4 is a view in elevation of one of the slats, Fig. 5 is a fragmentary view in elevation of one sprocket and related parts,

Fig. 6 is an exploded view in perspective showing the construction of the interlocking connection between a slat and its guide, and

Fig. 7 is a view on an enlarged scale showing 50 the flexing of a skin between the hold-down and a slat.

The working parts of the machine are supported at convenient height by a rectangular frame including four uprights 10 connected by suitable cross braces. Between the upper ends of both pairs of front and rear uprights are rigidly connected side beams 11 disposed in parallel relation and inclined upwardly and rearwardly at an angle of about 15° to the horizontal. A pair of spaced cross bars 12 and 13 are bolted to and supported in edgewise position upon the side beams 11. A pair of spaced longitudinally disposed guide bars 14 and 15 are secured flatwise between them the operative zone of the machine, which it will be seen is inclined upwardly and away from the operator who stands in front of the machine, or to the right of it as shown in Fig. 2. In the inner edge of each guide bar 14 and 15 is provided a square slot or groove 16, as best shown in Fig. 6. The upper and lower faces of the groove 16 are lined with steel wear strips and the upper corner portion of each bar is cut away so that the steel wear strip on the lower

face of the groove 16 is uncovered and exposed in the guide bar.

Secured to the front ends of the side beams 11 and the guide bars 14 and 15 is secured a stationary skin-holding or retarding board 17. This is transversely corrugated and inclined downwardly and rearwardly at an angle of about 30° to the vertical and is about waist-high. One end of the skin to be treated may be draped over 10 or in front of this board and frictionally held in place thereon by pressure of the operator's body. A guard in the shape of a transverse board 18 is secured flatwise between the forward ends of the guide bars 14 and 15 and above the upper 15 edge of the skin-holding board 17. All the parts thus far described are stationary elements of the machine. In operation tension in the skin is developed between the end thereof, which is frictionally held against the stationary board 17, and 20 the body of the skin held against traction slats which move away from the board 17 between the guide bars 14 and 15.

Bearings 19 and 20 (Fig. 3) are secured to the side beams 11 near their rear ends and in 25 these bearings is journaled a transverse shaft 21. The shaft 21 carries at one end a sprocket 22 about which extends a chain 23 running downwardly to a sprocket on a counter shaft 24 mounted in bearings on the two rear uprights of the 30 frame and driven through belt connections with a motor 25 also supported in the machine frame. The driving connections pointed out are designed to make a substantial reduction in the speed of the driven shaft 21 as compared to the speed of 35 the motor shaft.

Bearings 26 and 27 are secured to the side beams 11 near the forward ends thereof and in these bearings is journaled a transverse shaft 28 carrying a pair of spaced sprockets 29. The shaft 40 21 carries a pair of spaced sprocket wheels 32 and 33 which are in longitudinal alignment with the sprockets 29 on the shaft 28. A pair of endless sprocket chains 30 and 31 run upon each pair of 45 sprocket wheels and carry between them a flight of slats 34 in which are formed substantially upright pressure surfaces. The shape of the individual slats is best shown in Figs. 6 and 7. The slats are somewhat longer than the space between the sprocket chains 30 and 31, and are secured to the chains by angle brackets 36 which are included as special side pieces in the sprocket chains; that is, in each chain the side pieces of certain spaced links are formed as angle irons 36 and these are screwed or otherwise secured to the flat face of one of the respective slats 34. Both ends of each slat are shouldered to form tongues 34 and these tongues fit and slide within the grooves of the guide bars 14 and 15 so that the slats are positively supported and held against twisting in their movement rearwardly from the holding bar 17 in the upper reach of their path. The upper surface of each slat is grooved to provide a pair of upwardly projecting ribs 35 each having an upright pressure face, shown in Fig. 7 as having a forward inclination of about 15°, and a segmental rear or following surface. These two surfaces between adjacent ribs define a flat bottom trough between them.

The ribs 35 are shaped as above described in order to cooperate with a hand tool comprising a flat part 40 having a transverse handle 41 and a downwardly projecting transverse blade 42. As shown in Fig. 7 this manually operated tool is pressed by the operator upon a skin of leather which has been placed over the slats with the

blade 42 deflecting the leather downwardly into the trough between the ribs of one slat, or between the ribs of adjacent slats, thus forming transverse fold vertices in the leather at the lower edge of the blade 42 and over the upper edge of the adjacent rib and pressing the leather against the forward face of the adjacent rib. The result of this treatment is to impart a yielding forward draft and tension to the skin which is held at its rear end yieldingly against the holding board 17. The amount of tension may be variably and very delicately controlled by the manipulations of the tool and also the location of the tensioned area in the skin, that is to say, the tension may be exerted symmetrically across the whole skin or it may be exerted in first one side area and then the other.

The operation of the machine will be apparent from the foregoing description. The skin is placed loosely upon the table of the machine as suggested in Fig. 1. Under these conditions movement of the slats beneath it is merely sufficient to smooth the skin rearwardly from the transverse guard 18. The operator then leans forwardly pressing the end of the skin against the holding board 17 and places the tool 40 upon the skin so that the blade 42 engages it against a slat which has been brought upwardly about the sprocket wheels 29 and is just moving out from beneath the guard 18. The tool 40, of course, is carried rearwardly by its engagement with the moving slat and the skin is yieldingly stretched rearwardly by the friction developed between the blade 42 and the pressure face of the rib and the draft of the skin itself about the edge of the blade and the edge of the rib.

In addition to the stretching function secured by tensioning the leather in this manner the spudding operation is effected by the abrupt bending of the fibres over the edges which deflect the leather as it slips rearwardly past them. The operator retains the tool 40 in position upon the selected slat until it has moved a convenient distance rearwardly or until it has reached the rear edge of the skin. When this happens the tool is lifted, brought forwardly, and placed in position to engage another slat and the operation is repeated until the skin has been thoroughly stretched and spuddled.

It will be noted that on account of the close spacing of the ribs 35 the operator is not delayed at all in placing the tool, but that a moving slat is always available in whatever position he may desire to engage the skin. As the slats reach the rear end of the bed they pass downwardly about the sprocket wheels 32 and 33 and are returned in unsupported condition in the lower reach of their path to the sprocket wheels 29 at the forward end of the machine.

The manually operated tool may be of any desired width, generally rectangular in contour and providing a flat pressure face of substantial area. It will be noted that the blade 42 projects downwardly from the rear part of the pressure face thereby leaving the major portion of the effective face in advance of the blade 42. While this arrangement is not essential it is decidedly advantageous in that it tends to hold the blade in operative position with respect to the friction face of the moving slat and also supplies convenient and sensitive means for regulating the effective pressure upon the skin being treated.

The skin lies entirely free on the slats of the machine until it reaches the blade of the hand tool. The operator is thus entirely free to select

the exact area in the skin on which he desires to operate and, of course, he may select a slat at any position in the flight for engagement with the blade 42 of the tool.

It will be noted that the bearings for the transverse shafts 21 and 28 are mounted on the longitudinal top beams 11 so that the whole top of the machine may be assembled as a complete unit and then bolted in place upon the legs of the frame.

Having thus disclosed my invention and described in detail one embodiment thereof for the purpose of illustration but not limitation, I claim as new and desire to secure by Letters Patent:

1. A leather stretching and spudding machine comprising a transverse skin-holding member, and a continuous flight of transverse slats movable away from said holding member in a path supporting a skin in position to be engaged by a manually operated blade for bending the skin over the advancing edge of any selected slat in the flight.

2. A leather stretching and spudding machine comprising a stationary transverse skin-holding board, a pair of sprocket chains driven in parallel paths extending at right angles to said board, and a series of slats connected at their ends to said chains and movable in a path supporting a skin in position to be locally flexed by a manually operated blade shaped to be engaged with selected slats with portions of the skin interposed.

3. A leather stretching machine, having in combination, a machine frame, a skin-holding bar supported horizontally in the frame at substantially the height of a man's waist, a power driven shaft journaled in the frame at a substantial distance in the rear of said bar, guides located between said bar and shaft, and a flight of traction slats driven by said shaft for movement in the guides in a direction away from said bar, the individual slats being prevented from twisting by said guides.

4. A leather stretching machine, having in combination, a machine frame, a stationary skin-holding member supported at the front of the frame, stationary guides extending rearwardly from said member, traction slats making interlocking sliding connections at their ends with said guides and being thereby prevented from twisting, and power operated means for moving said slats along said guides.

5. A leather stretching machine, having in combination, a machine frame, a stationary skin-holding member supported by said frame, an endless flight of traction slats shaped at their ends for engagement with portions of the frame and guided thereby for movement in an endless path which is disposed in part adjacent to and at the rear of said skin-holding member, and power operated means for continuously moving the flight of slats in its path while the individual slats are prevented from twisting by their said engagement with the frame.

6. A leather working machine, having in combination, a frame, a stationary holding member at one end of the frame, an endless flight of traction slats movable upwardly behind said holding member and then laterally away from it, and stationary guideways for positively guiding the slats as they move laterally and preventing them from twisting as they are so moved.

7. A leather working machine, having in combination, a frame, a stationary holding member at one end of the frame, an endless flight of traction slats movable upwardly behind said holding

member and then laterally away from it, each slat having flat tongues at both ends, and stationary guides grooved to receive said tongues while the slats move laterally.

8. A leather working machine, having in combination, a frame, spaced sprocket wheels aligned longitudinally in the frame, sprocket chains running over said wheels in parallel paths extending from front to rear in the machine, a holding member extending transversely in front of the foremost sprocket wheels, a flight of traction slats secured to said chains and movable in otherwise unsupported condition in the lower reach of the chains, and guides for positively holding the slats against tipping in their movement in the upper reach of said chains.

9. A leather working machine, having in combination, a frame, a continuous flight of traction slats each having an upright friction face and a curved following face, a stationary holding member adjacent to one end of the path of said slats, said slats being movable in a path supporting a skin in position to be engaged by a tool having a portion for engaging the following faces of said slats and a downwardly projecting blade for cooperation with the upright friction face of one of said slats in sinusously deflecting a skin supported on the slats.

10. A leather working machine having a holding device and a flight of slats movable relatively therefrom, each slat having an upright friction face, and all of the slats being movable in a path supporting a skin in position to be engaged by a cooperative leather flexing device having an extended flat surface for engaging the leather in substantially flat condition above the slats and a blade projecting downwardly adjacent to one edge of said flat surface for deflecting the leather into contact with the upright face of any selected slat in the flight.

11. A machine for staking, stretching and spudding skins of glove leather, comprising a frame having an upwardly and rearwardly inclined top, a driven shaft journaled in the upper rear part of the frame and carrying a plurality of spaced sprocket wheels, an idle shaft journaled in the upper front part of the frame and carrying corresponding sprocket wheels, endless chains running rearwardly and upwardly over said sprocket wheels, a flight of closely spaced slats secured to said chains, stationary means for guiding the ends of the slats and holding them against twisting while in motion, and a holding member in-

clined forwardly and downwardly in front of said idle shaft, the said slats being movable in a path supporting a skin in position to be engaged by a leather flexing blade cooperating with any selected slat of the flight.

5 12. A machine for treating skins of leather, comprising a frame, and a top unit detachably mounted thereon and comprising longitudinal guideways, spaced transverse shafts with sprocket wheels thereon, endless chains running on said wheels, transverse slats carried by the chains and sliding at their ends in said guideways, and a transverse holding member extending across the front end of the unit, the said guideways 10 preventing twisting of the slats by their sliding engagement therewith.

13. A leather working machine comprising spaced parallel longitudinal guide bars defining the operative zone of the machine, endless chains 20 driven in paths below the plane of said guide bars, an endless flight of transverse slats secured to said chains with substantially no space between the slats and being disposed with their upper faces in a plane approximating that of said 25 guide bars and thus providing with the bars a substantially continuous exposed leather-supporting face.

14. A machine for stretching glove leather, comprising a frame, longitudinal guides supporting an endless flight of closely spaced leather-flexing slats movable in a fully exposed path and providing a substantially continuous ribbed support for a skin of leather, and a stationary snubbing bar supported by the frame adjacent to the 30 path of the slats, the said slats being movable in a path supporting a skin in position to be engaged by means for flexing any selected area of the skin in cooperation with the slat that happens to be moving beneath it.

40 15. A machine for stretching glove leather, comprising a frame, a horizontal snubbing bar supported thereby, spaced longitudinal guides defining a table-top zone between them and behind said bar, a flight of leather-flexing slats 45 supported by the guides and movable as a substantially continuous ribbed support upon which the leather may be supported in position fully exposed to the inspection of the operator and to be engaged by a loose blade whereby any area of the leather selected by the operator may be flexed in cooperation with the particular slat that happens to be moving beneath it.

WILLIAM GREEN.
